(57) **CLAIM**

We claim the ornamental design for a gel nail polish tube and brush applicator, as shown and described.

DESCRIPTION

FIG. 1 is a front perspective view of the gel nail polish tube and brush applicator.

FIG. 2 is a front view thereof, the rear view being a mirror image.

FIG. 3 is a left side elevation view thereof, the right side elevation view being a mirror image.

FIG. 4 is a bottom view thereof.

FIG. 5 is a top plan view thereof.

FIG. 6 is an exploded perspective view thereof.

FIG. 7 is an reverse exploded perspective view thereof.

FIG. 8 is an exploded front view thereof, the exploded rear view being a mirror image; and,

FIG. 9 is an exploded left side elevation view, the exploded right side elevation view being a mirror image.

The broken lines shown are for illustration purposes only and form no part of the claimed design.
